CHICKEN BROODER

Albert L. Kaysing, St. Louis, Mo., assignor to J. A. Smith Company, St. Louis, Mo., a partnership composed of Albert L. Kaysing, T. D. Shaffer, and S. B. Margulis

Application May 4, 1942, Serial No. 441,640

2 Claims. (Cl. 119—32)

This invention relates to devices generally called chicken brooders, and wherein chicks are placed soon after they have been hatched, so as to remain sheltered and heated for the required number of weeks that it takes to have said chicks sufficiently grown to be either marketed or otherwise shifted to other quarters.

The invention has among its objects the construction of such a device that will be neat and attractive in appearance, extremely simple to build from materials easily obtainable, of low cost, which will be serviceable for long periods, and which will be otherwise satisfactory and efficient for use wherever deemed applicable.

One of the primary objects of my invention is to so construct a brooder of the kind described, that it will accommodate a maximum number of chicks for its over-all size, and maintain every portion of the shelter or hover of the same at substantially the same temperature, so that the chicks will have no need to crowd together to keep warm, and there will be no sweating, chilling or other objectionable disturbances that might harm the chicks while in the hover.

Another object of my invention is to so construct a device of the kind set forth, that although a heater that requires oxygen to support its combustion is used therein, yet the heater is so placed as to be completely sealed from the chamber wherein the young chicks are sheltered, with conducting means therebetween for transferring the heat from said heater to said chamber in such a manner that the gases of combustion do not enter said sheltering chamber.

A further object of the invention is to construct a brooder of the kind described, wherein the heat transferred to said chamber from said outside source, will be of substantially uniform degree throughout said chamber, and will be directed downwardly onto the backs of said chicks in the chamber.

An added object of my invention is to so construct the brooder aforesaid, that the sheltering chamber or hover may be expanded so as to provide more head-room for the chicks, as said chicks grow bigger from week to week.

A still further object of my invention is to so construct the parts of the brooder, that the floor of the chick hover is readily removable, for cleaning or for any other reason simply by lifting the same out of the brooder, the heat transfer means that cooperates with the heater being fixed to said floor section so as to be removed therewith and thus provide a clear and unobstructed opening at the bottom of the said chamber when said

floor section with attached heat-transfer means are removed as a unit.

Many added objects and advantages of the construction herein shown and described will be obvious to those skilled in the art to which this invention appertains, as will be apparent from the disclosures herein given.

To this end, my invention consists in the novel construction, arrangement and combination of parts herein shown and described, and the uses mentioned, as will be more clearly pointed out in the following specification.

In the drawing, wherein like reference characters indicate like or corresponding parts throughout the views,

Figure 1 is a perspective side view of my device; and

Figure 2 is a longitudinal cross-sectional view of the same, as mounted directly on the ground, and showing only the adjacent portion of the exercise yard.

Referring more particularly to the drawing, wherein I have illustrated a preferred embodiment of my invention, there is shown a brooder adapted to comfortably receive and shelter a number of chicks that have been recently hatched, and to keep them warmed while they remain in said brooder, so that they will remain healthy and grow steadily until they are ready to be discharged ready for market or other disposition.

A frame consisting of a pair of spaced opposed end walls 1—2, connected by opposed spaced side walls 3—3, forms the supporting structure for the rest of the device. At a point intermediate the length of the side walls 3—3, a movable end closure, as in the form of the gate or door 4 shown, is positioned to define the limits of the chick-warming chamber or hover.

Although the brooder may be set on a table, or other wooden supporting structure, I have shown the device as set on an earthen floor, as in the latter instance, a separate container for the heater need not be built, inasmuch as the required size of excavation is quickly and easily made, as indicated at 5, below the floor level 6.

This excavation chamber is to be made large enough to accommodate the heater 7 therein, preferably supporting the latter on one or more rods 8 to lift it an inch or so off the ground, and so that the top of the heater chimney is about four inches from the heat-receiving means carried by the removable floor of the chick-receiving chamber, as will now be set forth in more detail. Before describing the latter, however, it is

to be mentioned now, that the excavated chamber 5 must be provided with free access to the outside air, so as to support combustion.

A substantially rectangular frame 9 is nailed or otherwise suitably fastened to the lower edge of the chick-receiving hover, preferably so as to come flush with the bottom edge of the walls 1 and 3. A series of boards or strips are fitted together as shown at 10 to neatly fit within the area defined by the frame 9, and are nailed or otherwise fixed to a pair of rods or stringers 11-11, the latter in turn resting on the frame 9 as shown when the floor is in place. Obviously, whenever the floor is desired to be removed, for cleaning or disinfecting the same, or for cleaning therebelow, it may be lifted out without difficulty—and just as easily and readily replaced.

A cover member comprising a top 12, fastened to a pair of side walls 13-13 and end walls 14-14 comprising a rectangle of substantially the size of the floor 10 is preferably detachably mounted on the open top of the chamber therebelow, as with side and end lugs 15.

A partition 18 is inserted to extend across the interior of the receptacle below said top 12, this partition being common to the upper and lower chambers thus formed, and being the roof of the lower chamber or chick-receiving hover 16, and the floor of the upper chamber 17.

This partition preferably slopes upwardly from its rear to its front edge, inasmuch as it has been found that this positioning is most effective in promoting good circulation of the heated air therebeneath, and is provided with vents 23-23 therethrough, grouped adjacent the rear and the front of said partition so that the pre-heated and fresher air from above said partition may enter through the same to the chamber 16 therebelow.

The forward edge of said partition is provided with an overhanging or downwardly directed flange 19 therealong, so as to direct the heated air from the under side of said partition downwardly toward the adjacent limit of said chamber 16.

Inasmuch as the chicks grow while in the brooder, I have provided compensatory means to keep pace with the varying size of the chicks, and to give more head-room to the same as they get bigger. To this end, I have arranged the partition 18, and which acts as the roof of the hover, to be adjustably raised from time to time. A supporting frame 20 is nailed to the side walls of the hover and may be detached and moved to a new position upwards of its original position every few weeks or so, or additional frames 21 may be fixed to the walls of the hover, spaced at any distance from the lowermost frame 20, so that the roof portion may be lifted out and re-set to its higher position with utmost ease. In such a manner, there is presented the minimum space to be heated, and a saving in the amount of heat used.

The upper chamber 17, and what might be termed a preheated fresh air intake chamber or hover, is provided with vents 22 through its top. The partition 18 is not as long as the length of the superimposed chambers 16 and 17, and its forward end terminates short of the adjacent ends of said chambers, thereby providing an air passageway 33 therealong between said pair of chambers.

A tubular element 24 is mounted substantially centrally of the floor 10, said element being open at its upper end and there being a plate 25 seal-

ing its lower end and projecting laterally of said tube, somewhat as shown, the tube extending upwardly through said floor and with said plate brought closely against the latter from below. 5 A thickness of asbestos or other suitable compressible packing means may be introduced between said plate and the opposed portion of the floor.

The tube 24 is of such a height that its top is about an inch or so below the under side of the roof 18 when the latter is in its lowermost adjusted position, and said tube is further provided with a series of apertures 26 through its side wall at a distance just a bit below the mid-height of said tube.

A conical-shaped deflector 27 is affixed to the under side of said roof section 18, and is a unit with the latter and demountable together therewith, the peripheral edge of said deflector overhanging the periphery of the tube and extending radially therebeyond for a substantial distance, somewhat as shown.

It will be understood from the foregoing description, that the tube and plate are a unit with the floor section 10 and removable from the box together therewith, by simply lifting said floor section.

All of the heat from the heater is directed to the plate 25, from whence a part travels upwardly through the material of the tube 24 and another part heats the air within the tube. Heat from the tube is not only radiated directly therefrom into the chick-receiving hover, but is directed against the deflector 27, which in turn directs the same downwardly and transversely to the far corners of the hover.

It has been found that chicks placed in a brooder of the construction hereinbefore set forth gives the chicks all of the room they need, but at the same time prevents "piling-up," evenly distributes the heat so that each chick is warmed individually and do not have to crowd together to keep warm, and directs the heat downwardly onto the backs of the chicks.

Spots too hot or too cold are avoided, and good ventilation is had, whereby the chicks get plenty of fresh air without drafts. The heat comes up through the floor, thus avoiding cold floors, there is more room in the hover for the chicks inasmuch as the heater is located outside the same, and there is no dead air, or gases as with a heater located within the same chamber as the chicks. None of the vital oxygen for the chicks is spent in feeding the heater, and the expansible chick-receiving hover permits more effective use of the heating medium to heat the space actually needed at any particular stage of growth of the chicks. Also, the double hover, one superimposed on the other, permits better ventilation without too great a heat loss.

The portion of the brooder shown to the right of the hovers may be used as an exercise yard or for feeding, the door 4 being provided with means as at 28 to cooperate with means at 29 on a cross bar 30 between the opposed side walls 3-3, to hold the door opened. Vents 31 may be provided through the walls 3-3, between the cross piece 30 and the wall 14 so as to insure ventilation therethrough at this point even while the door is held open.

Having thus described my invention, it is obvious that various immaterial modifications may be made in the same without departing from the spirit of my invention; hence I do not wish to be understood as limiting myself to the exact form,

arrangement, construction and combination herein shown and described, or the uses mentioned, except as limited by the state of the art to which this invention appertains, or the claims hereunto appended.

What I claim as new and desire to secure by Letters Patent is:

1. In a chick brooder, a housing having a partition thereacross to form an upper and a lower chamber, said partition normally being lower at its rear than at its front and provided with a downwardly directed flange along said front, said front terminating short of the length of said chambers so as to provide a vertical passageway between said front and the adjacent wall of said chambers; a heater entirely below said lower chamber; tubular means in said lower chamber and having its lower end completely sealed, and

spaced from said heater to transfer heat from the latter into said lower chamber, and a conical deflector at the under side of said partition above the tubular means to direct the heat laterally into said lower chamber.

2. In combination with a heater, a portable brooder having upper and lower chambers, said lower chamber consisting of side walls provided with an inwardly-directed flange at its lower end, a floor removably supported on said flange and having an opening therethrough, and tubular means provided with an imperforate bottom entirely sealing said opening so as to prevent all passage therethrough and constituting a heat-exchange means to radiate the heat from said heater into said lower chamber.

ALBERT L. KAYSING.
